UNITED STATES PATENT OFFICE.

WILLIAM O. ANDERSON, OF UTICA, NEW YORK, ASSIGNOR OF ONE-HALF TO
FABIAN HEDGES, OF ROCHESTER, NEW YORK.

EGG-CRATE.

SPECIFICATION forming part of Letters Patent No. 718,807, dated January 20, 1903.

Application filed March 7, 1902. Serial No. 97,080. (No model.)

To all whom it may concern:

Be it known that I, WILLIAM O. ANDERSON, of Utica, in the county of Oneida, in the State of New York, have invented new and 5 useful Improvements in Egg-Crates, of which the following, taken in connection with the accompanying drawings, is a full, clear, and exact description.

This invention relates to improvements in 10 egg-crates.

The object of my invention is to economize in the space necessary for the storage or transportation of large quantities of eggs.

Another object is to construct a crate of a 15 series of separate trays which are linked to each other in such manner as to be folded one upon the other to form an integral crate or unfolded so as to arrange the trays edge to edge in substantially the same horizontal 20 plane for facilitating the packing of the eggs in their respective supports, said crate being provided with suitable lids at the top and bottom, which are also linked to the adjacent trays and are adapted to be similarly folded 25 or unfolded when transporting or packing the eggs.

A further object is to provide clamping means secured to the lids, whereby the act of clamping the lids in position serves also to 30 hold the trays in their operative position.

A still further object is to form the trays in such manner that when assembled one upon the other a suitable space is left between the trays and lids, whereby free circulation of 35 air is permitted through the crate around the eggs inclosed therein.

A further object is to provide each tray with a series of lengthwise substantially parallel bars composed of sections, between 40 which sections are inserted a series of wire loops for the purpose of yieldingly supporting the eggs between adjacent bars, the adjacent faces of the upper sections of the adjacent bars being beveled or inclined upwardly from their bases for the purpose of reinforcing the bars and facilitating the reception and retention of the eggs in their 45 holders.

To this end the invention consists in the 50 combination, construction, and arrangement

of the parts of an egg-crate, as hereinafter fully described, and pointed out in the claims.

Referring to the drawings, Figure 1 is a perspective view of an egg-crate embodying the various features of my invention and 55 shown in its closed position as used in storage or transportation. Fig. 2 is a transverse sectional view taken on line 2 2, a few of the eggs being shown as inserted in their holders. Fig. 3 is an end elevation of the several trays 60 and lids, shown in their unfolded or extended position. Fig. 4 is a longitudinal sectional view through one of the trays. Fig. 5 is an enlarged detail view of a portion of one of the lengthwise egg-supporting bars. Fig. 6 65 is a transverse view of one of the detached wire loops or egg-holders. Fig. 7 is an end elevation of the several trays and lids showing the manner of folding and unfolding the same. 70

Similar reference characters indicate corresponding parts in all the views.

As shown in the drawings, this egg-crate comprises a series of trays 1, 2, and 3, lower and upper lids 4 and 5, links 6, 7, 8, and 9, 75 connecting the trays and lids, and clamping members 10 and 11 for securing the trays and lids in their folded position. The trays 1, 2, and 3, of which there may be any desired number, are identical in construction 80 and when folded to their closed position, as seen in Fig. 1, are disposed in planes one above the other and normally rest upon each other, with their sides and ends in substantially vertical alinement, and the lids 4 and 85 5 serve as bottom and top walls for the crate and when in their closed position normally rest against the lower and upper edges, respectively, of the bottom tray 1 and top tray 3. Each of these trays is usually open at 90 its upper end, and consists of side and end walls 10' and 11', a series of substantially parallel lengthwise bars 12, and wire loops 13. Although these trays are preferably rectangular in form, it is evident that they may be 95 otherwise formed, if desired, the side walls 10' being preferably of slightly less width than the end walls for forming lateral lengthwise openings 14 between the meeting edges of the trays when they are assembled or in 100

their closed position, as seen in Figs. 1 and 2, for transportation or storage, these lateral openings serving to permit a free circulation of air through the crate and around the in- 5 closed eggs, and it is therefore evident that the end walls 11' are of greater width than the side walls 10', and when the trays are folded to their closed position their edges en- 10 gage each other and the lower and upper edges of the lower and upper trays are en- gaged by the lids 4 and 5.

The bars 14 are preferably arranged length- 15 wise of the trays, substantially parallel and in separated relation to each other, for forming openings 15 between their adjacent edges, and are suitably secured at their opposite ends to the end walls 11' in proximity to the lower edges of the tray, the lower faces of said bars being arranged in a plane substan- 20 tially coincident with the lower edges of the end walls 11'. Each of these bars preferably consists of lower and upper sections 16 and 17, the lower section 16 preferably consisting of a substantially flat thin bar having its op- 25 posite ends secured to the end walls 11, and the upper bar 17 is preferably triangular in cross-section, with its base resting upon the bar 16 and its apex uppermost for forming upwardly-inclining faces 18, said section 17 30 being secured to the bar 16 and to the end walls 11 by nails or other suitable fastening members not necessary to herein illustrate or describe. Each of these bars 12 is provided with a series of yielding egg-holders, as 13, 35 which preferably consist of wire loops ex- tending upwardly from the adjacent edges of the bars 16 and having their opposite ends bent laterally and upwardly, the lateral portions being impinged between the sections 16 and 17, and the upwardly-extending por- 40 tions are inserted into the base of the sec- tion 17.

It is apparent from the foregoing descrip- 45 tion that the adjacent edges of the upper sec- tions 17 of the several bars of each tray are inclined upwardly from each other, and the loops at the adjacent edges of the bars 12 are arranged in pairs, each pair serving to receive and support each egg separately from the 50 others. It is also apparent that the triangu- lar-shape sections 17 not only serve to reinforce or strengthen the bars 12, but also en- able me to pack or store a larger number of eggs in the same-size tray than would be pos- 55 sible if the bars were of the same size as the lower section 16, the adjacent beveled edges also serving to additionally separate the eggs, which when inserted in position usually ex- 60 tend into the openings 15, as seen in Fig. 2. The links 6, 7, 8, and 9 are preferably ar- ranged and properly secured at both ends of the crate, the links 6 serving to connect the lower lid 4 with the tray 1, the links 7 connect- 65 ing the trays 1 and 2, the links 8 connect- ing the trays 2 and 3, and the links 9 connect- ing the tray 3 with the upper lid 5, these links being pivotally connected to the trays

and lids in such manner as to permit the trays and lids to be unfolded or extended to sub- 70 stantially the same horizontal plane, as seen in Fig. 3. When the trays and lids are thus unfolded, it is apparent that the eggs may be readily inserted or packed in between the loops 13 and that when the trays are entirely filled they may be readily folded one upon 75 the other to the position seen in Fig. 1 and as previously described.

I preferably employ two clamping members 10, one at each end of the crate, each of which preferably consists of a substantially U- 80 shaped bar pivotally mounted upon the upper face of the upper lid and having its opposite arms adapted to engage or interlock with the clamping members 11, these latter members usually consisting of screws or suitable lugs 85 secured to the side edges of the lower lid 4 when the crate is in its closed or folded position.

In order to hold the clamping members 10 in their inoperative position, I usually pro- 90 vide the upper lid with suitable sockets 20, in which the angular ends of said clamping members are inserted when the crate is being filled or when it is desired to unfold the same.

In the operation of my invention the crate 95 is first unfolded to the position seen in Fig. 3 and is laid upon the floor or upon other suitable support, with the open sides of each tray up- permost. The eggs are then inserted in the holders 13, and if it is desired to test the eggs 100 the several trays in their extended position, with the eggs therein, may be placed upon suitable supports, so that the lower faces are exposed, and a light may be then passed under each row of the eggs in the usual manner 105 for testing eggs without removing the same from their trays. After the eggs have been thus tested the several trays are folded one upon the other and the clamps 10 are en- gaged with the clamping members 11, there- 110 by locking the trays and lids firmly to each other and forming a substantially integral crate. The upper lid 5 is preferably extended beyond the end walls 11 and is formed with cleats 21, which serve as suitable handles 115 whereby the crate may be readily conveyed from one place to another.

The operation of my invention will now be readily understood upon reference to the foregoing description and the accompanying 120 drawings.

Having thus described my invention, what I claim, and desire to secure by Letters Patent, is—

1. An egg-crate comprising a plurality of 125 trays open at its top and bottom and each connected to swing one upon the other so as to lie in planes one above the other and also in the same horizontal plane, each tray having a series of upwardly-projecting yielding egg- 130 supports.

2. An egg-crate comprising a plurality of trays open at the top and bottom and connected to swing one upon the other so as to lie in

planes one above the other and also in the same horizontal plane, means for clamping the trays in the former position, and egg-supports for each tray open at both ends to expose the egg from the top and bottom of the tray.

3. An egg-crate comprising a plurality of egg-supporting trays and lids successively connected to each other to swing to planes one above the other, and also to lie in the same horizontal plane, said trays having substantially parallel openings therethrough and egg-holders projecting upwardly from opposite sides of the opening.

15 4. An egg-crate comprising separate trays, a link connecting the trays in such manner that one tray will swing upon the other from a position above the other tray to a position at one side of said other tray without inverting the swinging tray, and yielding egg-supports for each tray.

5. An egg-crate composed of a series of separate trays, having side and end walls forming the side and end walls of the crate, links 25 pivotally connecting adjacent trays, separated bars secured to the end walls and separate egg-supports projecting upwardly from each bar.

6. An egg-crate composed of separate trays 30 of uniform size, adjacent trays being linked to each other to swing to a position directly over each other and to a position side by side, lids linked to the end trays, and means for clamping the trays and lids in their closed position.

7. An egg-crate composed of separate trays, links connecting the trays, lids for the end trays, links connecting the end trays and lids, a clamp to lock the lids and trays in their 40 closed positions, and yielding egg-supports in each tray.

8. An egg-crate comprising separate trays

linked to each other to swing above and at the side of each other, each tray having side and end inclosing walls to form a frame open 45 top and having a series of openings in its bottom, the side walls of one tray resting on the side walls of the adjacent lower tray and a series of wire loops arranged in pairs and projecting upwardly from the sides of the 50 opening and of less height than the inclosing walls.

9. In an egg-crate, separated bars composed of sections and wire loops projecting upwardly from adjacent edges of the bars and 55 having their opposite ends inserted between the sections of their respective bars and driven into one of the sections.

10. In an egg-crate, separated bars composed of sections and wire loops projecting 60 upwardly from adjacent edges of the bars and having their opposite ends bent laterally between the sections, the extremities of said loops being bent at an angle with the lateral extension and inserted in the upper of the 65 sections.

11. An egg-crate comprising separate trays linked to each other to swing in the same vertical and horizontal planes to close and open the crate, portions of the adjacent edges of 70 the trays projecting beyond other portions to form openings between the meeting edges of the trays to permit the circulation of air through the crate above and beneath the eggs and a series of egg-holders carried by each 75 tray between the planes of its upper and lower edges.

In witness whereof I have hereunto set my hand this 27th day of February, 1902.

WILLIAM O. ANDERSON.
